METHOD OF PRODUCING PAPER DRUM CONTAINERS

Arthur L. Scott, Columbus, Ohio

Application October 16, 1947, Serial No. 780,173

2 Claims. (Cl. 93—36.8)

1

This invention relates to containers and methods of making the same. In particular, it is concerned with a container, the walls of which comprise a plurality of convolutions of a continuous strip and the closed end of which is formed in a novel manner.

Containers of laminated paper, fiber, or the like, are common place at the present time and their superiority, in many respects, over those of metal, for example is well recognized. As important advantages may be mentioned their lightweight and ability to withstand abuse in handling and shipping. The latter advantage, however, has heretofore been greatly lessened in the case of cylindrical containers because of the difficulty in producing a truly strong bond between the container wall and the end closures. The joint between the wall and an end piece is intrinsically a point of weakness because it occurs at both a discontinuity in the contour and a discontinuity in material. While the more or less abrupt corner must usually be retained because of the practical necessity for flat ends upon which the container may stand or with which it may abut its neighbors in the saving of storage space, the ideal construction would be one in which the material of the wall passed continuously into that of the end. Not only would maximum strength be thus obtained but also economy in the avoidance of fastening devices such as crimping bands.

The primary object of the present invention, therefore, is to provide a cylindrical container having integral side and end walls.

Another object is to provide a method of making such a container without waste of material, the blanks for two containers or for a container and its removable cap being complementary in outline and thus derivable from a single strip.

Still another object is to provide a construction for such a container which will render it highly impervious by reason of multiple overlapping of its elements.

These objects I accomplish by means of a blank having a serrated edge. The serrations take the form of elongated triangular tabs with triangular notches therebetween, the length of the triangular tabs equalling the radius of the finished container. The blank is wound upon a mandrel of the desired size with the tabs projecting beyond it. The tabs are then bent inwardly against the mandrel end, preferably in a progressive fashion as they reach the mandrel in the winding process.

The width of the tab bases is so chosen that a large number of them, say twenty to twenty-five, occur on the container circumference, whereby the distortion in bending over the arcuate edge

is minimized. The tabs reach to the center and lie in an edge-to-edge fashion as segments of the circle. When a complete turn has been made upon the mandrel, the end is completely covered by the tabs, the last tab being more than sufficient and thus overlapping the first. Due to this initial overlap, each tab of the new layer overlies a junction in the preceding layer and as the winding progresses a completely impervious structure results.

Both the zone of weakness where the sharp points of the tabs meet at the center and the tendency of the tabs to retreat from the center due to the increase in radius as the winding progresses are attended to in a simple and effective manner. A plurality of discs, of the same material as the blank, are interposed between the various layers of tabs. Where a flat outer surface is desired, a recess is formed in the mandrel end to accommodate the increased number of thicknesses. The length of tab is so chosen that the points of the outer layer meet at the center. The points of the inner layers would overlap the center by progressively greater amounts, due to the decreasing radius of the turns on the mandrel, if it were not for the fact that they need to bend progressively deeper into the recess as the number of discs increases. This number may be so chosen that the compensation is practically exact.

It will be understood that some form of bonding occurs between the layers. The stock may be impregnated with a thermoplastic or thermo-setting material and appropriately treated during the formation or after completion of the container, or a simple adhesive may be applied as the stock approaches the mandrel.

Wastage of stock is eliminated since the serating produces two blanks, each having triangular tabs and notches, which are both usable.

In the drawings, Fig. 1 is a diagrammatic perspective view illustrating a method of making a container and a closure therefor;

Fig. 2 is a bottom plan of a container;

Fig. 3 is a sectional view taken on the plane 3—3 of Fig. 2;

Fig. 4 is a plan of a serrated strip showing the two blanks derivable therefrom;

Fig. 5 is a perspective view of a closure or container cap made according to this invention;

Fig. 6 is a similar view of a container;

Fig. 7 is a longitudinal, medial section of a container illustrating the contour but omitting the fine structure of the wall and end; and

Fig. 8 is an enlarged radial section showing the structure of part of the container end and adjoining wall.

In the drawings, a preferred form of my con-

tainer is illustrated, along with an indication of a method for making it. In Fig. 1 a web or strip of material 10 is shown as being drawn from a supply roll and passing through a pair of serrating dies 12 and 13. The strip is thus separated into two blanks 14 and 15, shown also in Fig. 4, each of which comprises a continuous strip 16 having integral triangular extensions 17 along one edge.

From the dies the blanks are led to mandrels or forms 20 and 21. In the set-up shown in Fig. 1 a container and its cap are being simultaneously produced. Accordingly, the form 21 is sufficiently larger in diameter than the form 20 to produce the desired fit of the finished parts.

The winding of the strips is done at the end of the mandrels whereby the serrations 17 are allowed to overhang. The latter are then bent at the edge of the form, all at one time at the completion of the winding or, preferably, progressively as they reach the mandrel.

The triangular portions are so proportioned that they fit together in edge-to-edge relationship as segments of the circular end. Theoretically, of course, it is not possible to form the arcuate bases of the segments, using a flat material, but in practice, where a sufficiently large number of segments are used, the bulging at the corners is hardly perceptible and is flattened down by succeeding layers. Similarly, the theoretical impossibility of having identical triangles produce segments of increasingly larger circles as the winding progresses is resolved in practice by a barely perceptible overlap or a minute separation of the edges. Here, again, succeeding layers cover all discrepancies.

The segments pertaining to a given convolution of the wall strip overlie the juxtaposed edges of those pertaining to the preceding convolution. This salutary effect is obtained by having the interval or spacing between successive serrations a non-aliquot part of the cylinder circumference. This is illustrated in Fig. 2 where it is evident that all segments after the twenty-third will close the joints below them, resulting in the interlocked pattern of Fig. 3. It will be evident that the joints in every second layer are prevented from coinciding by the increasing circumference.

To close any opening which may be left at the center and to reinforce the slender tips of the segments, it is preferable to apply discs 25, usually of the same material, which are of sufficient size to cover the zone of weakness. Any appropriate number of discs may be included, depending upon the material used and the service to which the container is to be put. In the average type of container it is preferable to start with a disc, which will thus be on the inner surface to prevent the lifting of the inner set of tips, and then to add an additional one at the completion of each convolution. This places one on the outer surface to prevent the lifting of the outer set of tips.

As shown in Fig. 1, the discs may be secured, by an appropriate applicator not shown, to the tips of individual serrations before they reach the mandrel. As these serrations are subsequently bent into position the discs assume their proper place at the center.

Figs. 7 and 8 illustrate the action of the discs 25 in compensating for the change in radius among the various convolutions. A recess is provided, in the mandrel end, of sufficient depth to accommodate the added thickness of the discs.

as illustrated at 26. The inner disc 25' enters the recess and the first set of segments 17 bend axially inwardly to lie thereon. As the number of discs increases, succeeding sets of segments are bent to lesser degrees. Because the segments are drawn radially outwardly to an increasing extent by the enlarging bend at 27, their inner tips can be made to remain practically at the center 28. The outer disc 25'' then completes the assembly and forms a continuation of the flat outer surface.

As previously mentioned, any appropriate form of bonding may be used to bind the layers. The strip may, for example be passed through and impregnating bath, not shown, or may have an adhesive coated thereon, as by applicators indicated at 30 in Fig. 1.

A container made according to my invention is illustrated in Fig. 6, and a cap therefor in Fig. 5.

20 The method is particularly well adapted to the production of the larger sizes of containers, say 10 gallons to 50 gallons, and results in a very durable article. As an example may be mentioned a test specimen, made of laminations of kraft paper, which was filled with 70 pounds of sand and then shipped by express and motor freight on seven round trips totalling 2,850 miles. Despite the severe abuse which this entailed, the container remained structurally sound.

25 30 While I have shown and described a single embodiment of my container it will be evident that the method may be extended to the production of various forms and modifications of that shown.

35 I claim:

1. A method of making a container comprising, serrating a strip of material, securing reinforcing discs to some of the serrations, winding the unserrated portion on a cylindrical form, 40 bending the serrations radially inwardly to produce a closed end and to cause the discs to overlie portions of preceding serrations, and causing contiguous layers of material to adhere.

2. A method of making a cylindrical container 45 and closure therefor comprising, longitudinally serrating a strip of material to produce a first strip having triangular extensions approximately equal in length to the container radius and an unserrated width equal to the container length and a second strip having similar extensions and an unserrated width equal to the closure length, winding the strips on cylindrical forms having container and closure diameters respectively, bending the extensions radially inwardly 50 to produce closed ends, and causing contiguous layers of material to adhere.

ARTHUR L. SCOTT.
